F. L. MacALEESE

TENSION GRIP.

Filed Jan. 31, 1920.

INVENTOR.
BY *Frederick L. MacAleese*
Franklin G. Neal
ATTORNEY.

UNITED STATES PATENT OFFICE.

FREDERIC L. MACALEESE, OF MILWAUKEE, WISCONSIN, ASSIGNOR, BY MESNE ASSIGNMENTS, TO THE FISK RUBBER COMPANY, OF CHICOPEE FALLS, MASSACHUSETTS, A CORPORATION OF MASSACHUSETTS.

TENSION GRIP.

Application filed January 31, 1920. Serial No. 355,406.

To all whom it may concern:

Be it known that I, FREDERIC L. MACALEESE, a citizen of the United States, residing at Milwaukee, county of Milwaukee, State of Wisconsin, have invented certain new and useful Improvements in Tension Grips, of which I declare the following to be a full, clear, and exact description.

My present invention relates to a tension grip especially adapted for use in winding rags upon rubber tubes prior to the vulcanization of the same.

It has for its object a grip which will insure the ready maintenance of the desired degree of tension of the rags.

It has for a further object a grip which will enable the operator to regulate or release the tension at will.

It has for a further object various constructional advantages and improvements in operating methods which will be apparent from the following specification and the appended claims.

In the manufacture of rubber tubing such as inner tubes for pneumatic tires it is customary to wrap the tube helically with "rags" or strips of cloth prior to vulcanization. These rags have been usually supplied wound upon a short length of pipe which is held in the hands of the operator during the winding process. The rags pass from the pipe over guides parallel to the mandrel on which the tube is mounted and the slip of the rags on the pipe or of the pipe in the operator's hands, together with the friction of the guides, gives the necessary tension. It can readily be seen that the tension thus produced is uncertain and subject to considerable variation. It is the object of my invention to provide a tension grip which will enable the old process to be carried out more expeditiously and with surer control over the tension.

By the ordinary method it requires a great amount of pressure by the operator's hands to get the desired tension, which causes fatigue, and the tendency to relax this pressure causes the wrapper to run freely without tension, thereby greatly increasing the possibility of making imperfect goods on

account of lack of pressure in the cure. By this invention any required tension may be obtained without fatigue by a slight movement of the hands, thereby securing a much better product on account of the uniformity of pressure applied.

My invention will now be described with particular reference to the accompanying drawings, in which—

Fig. 1 is a plan view showing the improved tension grip in use;

Fig. 2 is a longitudinal section of the rag holding sleeve;

Fig. 3 is an elevation of the tension grip with the rag holding sleeve removed and with certain other parts partially broken away;

Fig. 4 is a transverse section on line 4—4 of Fig. 3; and

Fig. 5 is a longitudinal section through the complete device, showing the rags in position.

The device comprises a sleeve 10, upon which the rags 11 are wound, and which is mounted for frictionally restrained rotation as will now be described. To a short shaft 12 are fixed handles 13 and 14, as by set screws 15 and 16. Loosely mounted on shaft 12 between the two handles 13 and 14 is a releasing handle 17. Mounted upon handles 17 and 14 are collars 18 and 19 respectively, supporting between them a sleeve 20. A helically wound spring 21, faced on its outer surface with a friction material such as leather 22, is secured at 23 to handle 14 and at 24 to handle 17. A projection 25, such as a set screw, on sleeve 20 serves to hold the sleeve 10 releasably in position through engagement with a branched slot 26. Lubrication is provided for by a screw 27 in a plug 28 in the end of handle 14. Oil or grease inserted through the opening presented by the removal of this screw will find its way inside sleeve 20 through oil holes 29.

The operation of the device is as follows: A rubber or other tube 30 to be wrapped is placed on a mandrel 31 and a sleeve 10 with a supply of rags 11 in place is positioned on sleeve 20 by engaging slot 26 with screw 25. The free end of the rag strip is caught

around the mandrel 31, the handles 13 and 14 grasped by the operator, and the mandrel set in rotation in the direction of the arrow. The rotation of the mandrel will wind on the rag strip, unwinding it from sleeve 10 and turning the latter, together with the sleeve 20, in the direction of the arrow applied thereto in Fig. 1. It will readily be seen from an inspection of Figs. 3 and 4 that as the sleeve rotates, its contact with friction band 21—22 will cause the latter to tend to move, or pile up, as it were, towards the end secured to handle 14. As this motion is prevented by handle 14 being held stationary the friction band will be forced outwardly against the interior of sleeve 20, thus increasing the friction to a definite limit determined by the slippage of the friction band on the sleeve. It is desirable to have band 21 made of spring material so that it will normally press outwardly against the interior of the sleeve with sufficient force to start the cycle of operations above described. It will be understood that during this cycle releasing handle 17 will have a slight initial rotation in which it will accommodate itself to the changed position of the friction band as the latter expands as described, and will thereafter remain stationary. If it is desired to reduce the tension with which the rag strip is being delivered the operator's left hand is moved onto handle 17 and the latter is turned relatively to handle 14 in the direction of the arrow in Fig. 3. This winds up band 21 slightly, moving its friction surface 22 away from the interior of sleeve 20 and obviously reducing the resistance to rotation of the latter to any desired degree. A like effect may be produced by holding handle 17 firmly and allowing handle 14 to turn under the influence of the friction of sleeve 20 transmitted through band 21, 22. By turning handle 17 in a direction opposite to that of the arrow in Fig. 3 a greater tension than the normal may be imposed on the rag strip. I realize that changes may be made in the structure and method of use set forth above without departing from the spirit of my invention, and desire to cover the latter in its broad as well as its specific aspect in the appended claims.

What I claim as new and desire to secure by Letters Patent is:

1. A device of the character described comprising a pair of handles, a releasing handle rotatable with respect to the first named handles, a helically wound friction band one end of which is secured to one of the first named handles and the other to the releasing handle, a sleeve inclosing the friction band and secured against axial motion relative thereto, and a rag holding sleeve releasably secured to the first mentioned sleeve.

2. A device of the character described comprising a pair of handles, a releasing handle rotatable with respect to the first named handles, a helically wound friction band, one end of which is secured to one of the first named handles and the other to the releasing handle, and a sleeve inclosing the friction band.

3. A device of the character described comprising a handle, a helically wound friction band having one end secured thereto, a sleeve encircling the friction band and being rotatable with respect thereto, and means for expanding and contracting the friction band.

4. A device of the character described comprising a handle, a sleeve mounted for rotation, and means operable either automatically or manually for causing and regulating resistance against rotation of said sleeve.

5. A device of the character described comprising a handle, a sleeve rotatable with respect to said handle, means for causing resistance to rotation thereof, and a rag strip retaining sleeve detachably mounted on said first named sleeve.

6. In combination, a pair of handles assembled to permit relative movement therebetween, a sleeve rotatably mounted thereon, and means carried by said handles adapted to resist rotation of said sleeve and controlled by said relative movement.

7. In combination, a pair of handles assembled to permit relative movement therebetween, a sleeve rotatably mounted thereon, and means carried by said handles within said sleeve adapted to resist rotation of said sleeve and controlled by said relative movement.

8. In combination, a pair of handles assembled to permit relative movement therebetween, a sleeve rotatably mounted thereon, and a helical brake band carried by said handles adapted to resist rotation of said sleeve and controlled by said relative movement.

9. In combination, a pair of handles assembled to permit relative movement therebetween, a sleeve rotatably mounted thereon, and a helical brake band carried by said handles within said sleeve adapted to bear against the inside of said sleeve to resist rotation thereof and controlled by said relative movement.

10. In combination, a pair of handles assembled to permit relative rotation therebetween, a sleeve rotatably mounted thereon, and means carried by said handles adapted to resist rotation of said sleeve and controlled by said relative rotation.

11. In combination, a pair of handles assembled to permit relative rotation therebetween, a sleeve rotatably mounted thereon,

and a helical brake band mounted between said handles adapted to resist rotation of said sleeve and controlled by said relative rotation.

5 12. In combination, a pair of handles assembled to permit relative rotation therebetween, a sleeve rotatably mounted thereon,

and a helical brake band mounted between said handles within said sleeve adapted to bear against the inside of said sleeve to resist rotation thereof and controlled by said relative rotation.

FREDERIC L. MacALEESE.
